ELECTROMAGNETIC ACTIVATING DEVICE

Madison P. McCarty, Dallas, Tex., assignor of ten and two-tenths per cent to Warner Clark, San Francisco, Calif., ten and two-tenths per cent to Leonard W. Orynski, Dallas, Tex., ten and two-tenths per cent to Graham B. Moody, Los Angeles, Calif., ten and two-tenths per cent to Earl R. Wall, McAllen, Tex., five and one-tenth per cent to R. H. Morrison and five and one-tenth per cent to F. A. Davies, both of Dallas, Tex.

Application June 16, 1932. Serial No. 617,512

4 Claims. (Cl. 172—126)

This invention relates to electro-magnetic motors and its has particular reference to certain new and novel improvements in electro-magnetic activating devices, employing as a means of operation, one or more peculiarly shaped and magnetically attracted armatures and an interrupter.

The principal object of the invention is to provide an improved application of electrical magnetism with which may be operated or driven certain mechanical devices of various kinds and types and under various circumstances and for different purposes, the degree of power obtainable being dependent largely upon the size and shape of the device to which the invention appertains and possibly from the manner in which the device is associated with or connected to the mechanical or other device to be operated thereby.

20 The invention comprehends the provision of an exceptionally simple application of magnetic energy to secure power to whatever extent needed for driving various kinds and types of mechanical contrivances, the improvement being such that the cost of construction, as compared with present types of electric motors and other sources of power is negligible and the cost for operating the present invention under any circumstances is but a fraction of the cost incident to the operation of known and conventional types of electrical power sources.

Primarily, the object of the invention is to afford an inexpensive yet extremely practical and dependable expedient for the purpose of intermittently making and breaking an electrical circuit, making the same peculiarly adaptable in a light circuit for vehicle stop lights, vehicle traffic control lights and for many other purposes where "blinker" lights are desirable or necessary for the promotion of safety and for other purposes. Current interrupters of the type generally known are usually of the inexpensive type of thermostats and are not dependable for the reason that they are short lived and their periods of interruptions are not uniform. Other mechanical and electrical types of interrupters are quite expensive and are objectionable for reasons familiar to those given in that they become impaired easily and are likely to be come useless at the time most needed.

The present invention comprehends the provision of a new and wholly practical device for the purposes specified and for other purposes too numerous to mention and whose construction is such that there is little likelihood that

it will become inopportune impaired, thereby affording an electrical unit upon which great dependence may be placed regardless of its application.

Yet another object of the invention is to provide a new application of magnetic energy whose movements in operation are unlimited, that is to say, by certain constructional variances, a rotative, oscillative or reciprocative motion may be obtained without departing from the broad principle of the invention. The rotative motion is of value when it is desired to impart such motion to a machine or apparatus. The oscillative motion may be used in connection with the interruption of an electrical current when the device is adapted as a current interrupter in light circuits and the like and the reciprocative motion is desirable for many uses and especially takes the place of the well known types of solenoids.

With the foregoing objects as paramount, the invention has particular reference to its salient features of construction and arrangement of parts, which will become manifest as the description proceeds, taken in connection with the accompanying drawings, wherein:

Figure 1 is a perspective view of one form of the invention with a portion of the exterior housing broken away.

Figure 2 is an underside view of the inner casing of the device shown in Fig. 1.

Figure 3 is a view similar to Figure 1, showing portions of the inner casing broken away and illustrating the interior working parts of the invention.

Figure 4 is an elevational view of the operative parts and base shown in Figure 3.

Figure 5 is a diagrammatic view of the wiring of an electrical light circuit in which the invention is arranged.

Figure 6 is one form of armature embodying the invention and used in connection with the devices shown.

Figure 7 is a modified form of armature.

Figure 8 is a modified form of device embodying the principle of the present invention in which the elements are designed to rotate instead of moving in an oscillatory manner as in the case of the device shown in Figure 1.

Figure 9 is a further modified form of armature, showing the laminated type.

Figure 10 is another form of armature for producing varying degrees of speed by the intensification of magnetic attraction.

Figure 11 is a further modified form of the

invention which serves in the capacity of a solenoid or imparts reciprocative motion.

Figure 12 is a side elevation of the operative parts of the device shown in Figure 8, and

5 Figure 13 is a wiring diagram showing the application of the device shown in Figure 1.

In continuing in more detail with the invention, it may be stated for the sake of clarification that while the invention broadly pertains to electro-magnetic motors, it is obvious that its application may be materially broadened to cover a field greater than herein expressed, and for that reason, it is not intended that the invention shall be limited to the specific applications defined herein. It has been stated previously that variance in the degree of size and shape of the parts of the invention will have the effect of varying the degree of power and speed obtainable. Accordingly, it is considered sufficient to define the prime uses for which the invention has been designed which are first, to provide means for incorporation in an electrical circuit for interrupting the current to a light, and second, to provide an electro-magnetic prime mover or motor.

With reference to Figures 1 to 4 inclusive, 1 designates a base which has a convenient mounting in the form of a non-insulated arm 2 and insulated arms 3, the insulation being 20 designated at 4 in Figures 3 and 4.

30 Connected to the center of the base and extending upwardly therefrom is a spindle 5 upon which is rotatably disposed a sleeve 6, integral with the inner casing 7. A collar 8, shown only in Figure 1, is placed over the end of the pin or spindle 5 and is thereby held stationary with respect to the said spindle 5, although the housing or casing 7 is capable of rotation on the said spindle. This rotation is limited to an 40 oscillating movement by a coiled spring 9, and the interrupter, the inner end of said spring being secured to the collar 8 at 10 while the outer end is secured to a stud 11 affixed to the top of the casing 7 as shown in Figure 1. Obviously, when the casing 7 is moved in a clockwise direction, spring 9 will have a tendency to return the same repeatedly and at accurately predetermined intervals to the starting position.

50 A plate 12 is provided on the underside of the top of the casing 7 and suitably insulated therefrom by a layer of fibrous material 13 between the said plate and the top and with small washers 14 of the same material interposed between the rivets 15, with which the said plate 55 is retained, and the top of the said casing 7. The plate 12 has a pair of depending stops 16 on opposite sides of the sleeve 6. The purpose of these stops will be explained presently. An 60 electro-magnetic coil 17 is mounted upon and grounded with the ferrous base 1 and is provided with a core having a relatively large pole end 18, as shown in Figure 3. The coil 17 is so disposed that upon rotation of the inner casing 7, the reduced end of a substantially 65 wedge shaped and curved armature 19, fixed to the inner wall of the casing 7, will be attracted by the magnet and due to the fact that the armature increases in width and thickness toward its opposite end, reluctance is gradually reduced and due to the magnetic flux flowing 70 through the face of the magnet 17, into and through the armature 19, thence through the base 1, a tensioning effect is produced which tends to exert a pull upon the armature 19, 75 thereby causing the casing 7 to move in a clock-

wise direction against the resistance of the spring 9.

Referring to Figure 4, it is pointed out that a pivoted switch 20 is provided and is maintained in either of two positions under tension by means of a spring 21. The peculiar manner in which the spring 21 is connected to the switch 20 and the manner in which tension is brought to bear thereon is important since it is through this medium that the current flowing through the device is periodically interrupted. The spring 21 holds the switch 20 in either one of the two positions of the latter shown in solid and in dotted lines in Figure 4. Consequently, as the casing 7 is moved in the manner explained in the foregoing by magnetic attraction, one of the stops 16 carried by the plate 12 in the casing 7 will engage the upwardly extending finger 22, integral with the switch 20, thereby reversing the 80 position of the switch to either make or break the circuit and momentarily suspend the flow of current through the device. Further explanation of this detail will be set forth presently. In the case of its use in connection with an automobile stop light, the device is so mounted on the frame of the vehicle that it will be properly balanced and the maximum strength of the spring 9 will be effective. The device is so arranged in the electric circuit of the vehicle that 90 current flowing through the binding post 23 will flow to the point 24 and when the switch 20 is in the position shown in solid lines in Figure 4, the current will flow through points 24 and 25 into the switch proper 20, thence through its 95 support 26, into the plate 27, through the coil wire 28 and into the coil 17, thence to ground through the ground connection 2. During the period of time the coil 17 is energized as just explained, the reduced end of the armature 19 100 is attracted and the tendency of the magnetic flux thus created to reduce the reluctance will cause the armature 19 to be moved as explained previously in a clockwise direction, thus moving the casing 7 accordingly until one of the stops 105 16 is revolved to a position to engage the upwardly extending finger 22 and move the same to the dotted line position shown in Figure 4. When this is done, points 24 and 25 are broken, thereby interrupting the current flowing through 110 the device and de-energizing the electro-magnetic coil 17.

Upon de-energization of the magnet 17, the casing 7 is released to the action of the spring 9, which returns the casing to normal starting 115 position or to such position that the opposite stop 16 will engage the opposite side of the upwardly extending finger 22, whereupon it is moved to the position shown in solid lines in Figure 4 and since the finger 22 is an integral 120 part of the switch 20, the latter is also moved to the position shown in solid lines, again making contact between the points 24 and 25 in order that the current may resume its flow through the device and the light or other device. The 125 foregoing operation is continued automatically as long as the current is allowed to flow through the circuit.

Figure 5 typifies the wiring diagram as applied to a vehicle and may also be taken to 130 represent any electrical circuit containing a light or any other electrical device operated by the circuit. The battery 29 is grounded at 30 and current flowing through wire 31, upon closing the switch 32, enters the switch 20 and flows 135

thence through contact points 24 and 25, through wire 34 to lamp or other device 33, thence returned to ground. Current also flows through wire 28 to coil 17, energizing the same, 5 thence to ground. The stops 16 are suggested diagrammatically in Figure 5 as opposing the upwardly extending finger 22 of the switch 20. Movement of these stops alternately against the finger 22 of the switch will obviously make and 10 break the circuit between the points 24 and 25. The coil in this figure is shown at 17 and grounded at 1, which represents the base of the device as shown in Figures 1 to 4 inclusive.

The foregoing description deals exclusively 15 with that type of instrument, embodying the principle of the present invention, designed primarily for the purpose of interrupting the electric current, especially a light current where a "blinker" effect is desired. The current is 20 broken at accurately timed intervals, the duration of the time intervals being predetermined in various ways. But varying the spacing of 25 the stops 16, changing the size and shape of the armature 19 or by changing the degree of throw of the switch 20, one may effectively change the duration of time during which the current may be interrupted.

Referring now particularly to Figure 8, it is 30 pointed out that the structure shown therein is not unlike the structure first described in principle, since substantially the same type of armature is employed but instead, the device imparts to its elements a rotary rather than an oscillating motion.

A pair of electro-magnets 35 and 36 are 35 provided in an iron mounting 37, which latter is supported upon an insulated base 38. The core of each coil is of the peculiar shape shown in Figures 8 and 12 and are designated at 39 and 40 for the coils 35 and 36 respectively. The 40 faces of the cores 39 and 40 are in vertical alignment as shown in Figure 12. When the coils 35 and 36 are first energized, there is a relatively high resistance to the flow of flux 45 between the pole ends 39 and 40 of the magnets, due to the comparatively wide air gap between the pole ends. The reduced end of one of possibly three of the armatures 41 is attracted by the lines of force and caused to move in a clockwise direction, thereby decreasing the reluctance 50 between the pole pieces of the magnet, by reason of the fact that the armatures become wider and greater in thickness at their remote ends. The circuit is intermittently made and broken 55 at predetermined intervals as the casing 42 is revolved in the manner explained to periodically energize and de-energize the magnets 35 and 36 and the inertia of the moving casing 42 carries the armatures successively into the range of 60 magnetic attraction of the magnets.

Current is introduced through wire 43, through the arm 44, to contact point 45 and when this point is engaged with contact point 46, carried by the arm 47, current flows through 65 the arm 47, wire 48 and into the coil 35, thereby energizing the same, thence through the adjacent coil 36 and out through wire 49. The two coils are thus energized simultaneously, thereby setting up a magnetic flux to establish 70 lines of force between the pole pieces 39 and 40, to thereby attract and move the armatures 41 in the manner explained in the foregoing.

It is necessary, in order to carry the armatures 41 over the low reluctance point, to interrupt 75 the current periodically. This is done by

means of a series of fibrous cams 50, disposed in spaced relationship about the top of the casing 42, as shown in the cutaway portion of the casing in Figure 8. As the casing 42 rotates on the central post or spindle 51, the cams 50 are moved successively against the end of the flexible arm 47, shown at the left of Figure 8. Upon engagement of one of the cams 50 with the free end of the arm 47, the latter is depressed to separate the points 45 and 46, thereby interrupting the flow of current through the device at this point. However, the inertia of the rotating casing 42 will continue to move the same to carry the armatures 41 over the points of low reluctance and since the current interruptions are momentary, re-energization of the magnets 35 and 36 is established immediately and which operation continues until the flow of current is discontinued in the circuit.

In order to lessen the friction occurring between the casing 42 and the post 51, a small anti-friction bearing 52 is provided in the top of the casing.

From the foregoing description, it will be seen that through the medium of an electro-magnet or a combination of electro-magnets, combined with armatures of the peculiar design and shape shown in the drawings, many and various movements may be obtained and applied to various uses. The type of current interrupter employed in connection with the invention is of secondary importance since it is obvious that there are many ways in which the flow of current may be periodically suspended during operation of either of the devices shown and described in the foregoing.

As an example of the different types of armatures which may be employed in connection with the invention, reference is made to Figure 7 which shows a wedge shaped and curved armature 53. This type of armature differs from the armature 19, shown in Figure 6 only in that it is of constant width throughout its length and varies in thickness only while the armature 19 varies both in thickness and in width. The armature 54 shown in Figure 9 is substantially the same as the armature 19 except that it is constructed of laminated material and is found to give substantially the same results as the armature 19.

In many cases, it is found that where irregular movements are to be imparted, the type of armature designated at 55 in Figure 10 is effective in that this armature is of irregular width and of graduated thickness. The obvious action of the electro-magnet on this type of armature would be a slow initial movement, terminating in a sudden quick movement or snap while in the other types of armatures shown and described the movement would be more or less constant with a possible increase in speed as the heavy portion of the armatures approaches the pole pieces of the electro-magnet.

Figure 11 merely shows substantially the same combination of electro-magnets disclosed in Figures 8 and 12 to illustrate the principle of the invention in obtaining a reciprocating movement. The coils 56 and 57 are wound upon an iron core 58 which is shaped to define an air gap 59 between the pole pieces 60 and 61. In this case, the armature 62 is of triangular shape and while the same general design is carried out in the construction of this armature, its thickness is constant and its triangular shape has been found to be effective in obtaining slower move-

ment, than that of the well known type of solenoid. The structure shown in Figure 11 is dia-
grammatic and purposely so since it is intended
only to show the principle of the invention
adapted to bring about a reciprocative move-
ment and accordingly, no means by which the
armature 62 may be guided relative to the poles
60 and 61 of the magnets has been illustrated.

With reference to Figure 13, it will be noted
that the wiring diagram therein shown is sub-
stantially the same as the wiring diagram shown
in Figure 5 except that a horn 63 is incorporated
in the circuit instead of the lamp 33 shown in
Figure 5. The battery 64 is grounded at 65 on
the frame of a vehicle and upon closing the
switch 66, current flows through wire 67 into
the pivoted switch 68, through contact points 69
and 70, the latter being insulated from each
other, thence through wire 71 to the horn 63.
The coil 72 is energized simultaneously through
the wire 73, and has the effect of actuating the
switch 68, by the application of the principle
of the invention embodied in the structure
shown in Figure 1. In other words, the switch
68 is rocked on its pivot to intermittently engage
and disengage the contact points 69 and 70 to
interrupt the flow of current to the horn 63
through wire 67, switch 68, points 69 and 70 and
wire 71. The flow of current is also interrupted
to the coil 72 of the invention, through wire 73.

Normally, the operating current to the horn
is through the above circuit so that upon closing
the switch 68, vibration will be immediately set
up in the horn, which will be continuous as long
as the points 69 and 70 remain closed. When
points 69 and 70 are opened by the mechanism
herein described, a lesser amount of current
flows through wire 74 and resistance 75 because
of the introduction of the resistor 75 in the cir-
cuit. The result is that a sound will be emitted
from the horn 63 having an alternate rise and
fall in pitch, therefore producing a novel effect.

It is obvious from the foregoing that the in-
vention is able to obtain a slow, regulated move-
ment of the armature and maintain control of
such movement which is a great improvement
over any conventional type of armature whose
movement is quick, unregulated and difficult to
control.

Manifestly, the construction shown is capable
of considerable modification and such modifica-
tion as is considered within the scope and mean-
ing of the appended claims is also considered
within the spirit and intent of the invention.

What is claimed is:

1. An electro-magnetic activator and switch
including electro-magnetic means and an arma-
ture movable across the face of said electro-
magnetic means and of such dimensions that
the reluctance of the magnetic path is decreased
as said armature is moved across the face of
said electro-magnetic means, an oscillatable
housing for said electro-magnetic means, arma-
ture and switch spring, means yielding to the
movement of said housing for returning the
same to its original position when moved by said
electro-magnetic means, an upwardly extending
lug carried by said switch and means carried by
said housing and intermittently engaging said
lug to actuate said switch to effect intermittent
energization and de-energization of said electro-
magnetic means.

2. An intermittent electric switch including a
base portion and a movable member pivoted to
said base portion, a contact point on said base
portion and a second contact point on said mov-
able member, tensioning means for maintaining
said contact points in either engaged or disen-
gaged relationship, means for limiting the move-
ment of said movable member, an oscillatable
covering for said switch and means carried by
said covering for actuating said switch.

3. An intermittent electric switch including a
base portion and a pair of standards carried by
said base portion, a movable member having a
substantially U-shaped cross section pivoted be-
tween said standards, a tension spring attached
to said base portion and extending upwardly
over said pivot and then downwardly within
said movable member and having pivotal con-
nection with the forward end of said movable
member, a tail portion on said movable member
to limit movement thereof, an upwardly extending
actuating lug integral with said movable member,
a contact point carried by said base and a second
contact point carried by the forward end of said
movable member.

4. A current interrupter including a base por-
tion and a pair of standards carried by said base
portion in spaced relationship, a member sub-
stantially U-shaped in cross section pivoted be-
tween said standards, an upright member on 120
said base portion, a tension spring attached to
said upright member and extending upwardly
over said pivot and then downwardly within said
U-shaped member and having pivotal connection
with the forward end of said U-shaped member,
a tail portion on said U-shaped member to limit
movement thereof, an upwardly extending actuat-
ing lug integral with said U-shaped member, a
contact point carried by said base and a second
contact point carried by the forward end of said
U-shaped member.
